CAR TOP CARRIER

Norman J. Bessette, 264 Vine St., Pawtucket, R.I.
Filed Oct. 26, 1961, Ser. No. 147,812
2 Claims. (Cl. 312—323)

This invention relates to a car top carrier.

One of the objects of this invention is to provide a car top carrier which may be a complete unit in itself adaptable to be mounted upon the top of an automobile.

Another object of the invention is to provide a car top carrier which will be of good storage capacity and which may be easily handled for loading and discharging.

A more specific object of the invention is to provide a car top carrier comprising a casing and a drawer which may be withdrawn from the casing and supported in a position alongside of the automobile in substantially a vertical attitude so that the contents thereof may be easily removed from the drawer.

Another object of the invention is to so arrange the drawer that in removing the same or positioning the drawer for movement into the casing in which it houses, it will be somewhat counterbalanced about a pivotal arrangement.

With these and other objects in view, the invention consists of certain novel features of construction as will be more fully described and particularly pointed out in the appended claims.

In the accompanying drawings:

FIGURE 1 is a perspective view showing a portion of an automobile with the car top carrier of this invention mounted thereon and in a position for loading or discharge;

FIGURE 2 is a sectional view on substantially line 2—2 of FIG. 3 and on substantially larger scale of a fragmental portion of the carrier illustrating the drawer as positioned within the casing and one of the tracks in end view with its associated parts;

FIGURE 3 is a longitudinal sectional view through the carrier on substantially line 3—3 of FIG. 1 with the drawer in housed position; and

FIGURE 4 is a sectional view of the carrier similar to FIGURE 3 but with the drawer in an intermediate position being partially swung to its discharge position.

In proceeding with this invention, I have provided a casing which is generally rectangular and has an open side, and I have mounted tracks or rails on the end walls of the casing which tracks will slide outwardly through the open side. A drawer is slidably and pivotally mounted on these tracks so that it may be slid into the casing through the open side, or when withdrawn to a certain position, it may be swung from a horizontal to a vertical position. The front of the drawer serves as a closure for the open side of the casing.

With reference to the drawings, the casing is designated generally 10 and the drawer which is housed therein is designated generally 11. This casing consists essentially of forward and rear end walls 12 which are arched as at 13 to provide foot portions 14. A shoe 15 is pivotally mounted as at 15' on each foot 14 and carries a cross bar 16 upon which two suction cups 17 and 18 are mounted while at the other end of the shoe, the third suction cup 19 is provided. By reason of this rockably mounted shoe, the suction cups may be adjusted to the convex curvature of the automobile top 20. A top wall 21 of sheet metal extends from one end of wall 12 to the other end of wall 20 and is continued and bent downward bulging outwardly as at 22 so as to provide a rounded and finished end. Ribs 23 may be formed in the top wall for stiffening the same. A bottom 23 is provided extending between the end walls 12 which is flanged as at 24 and secured to the end walls by some fastening 25. One side of the casing

2

is closed by any suitable wall such as 26 while the other side of the casing 27 is open.

At spaced locations such as shown in FIGURES 3 and 4, wheels 30 are mounted on fixed axles 31 which extend inwardly from the inner surface 32 of the forward and rear end walls 12 (see FIG. 2). The wheels 30 on the end walls 12 are located at a definite distance from the closed side wall 26, while the other wheels 30' are located adjacent the open end 27 of the casing. These wheels support tracks 33, each of which is generally S-shaped in cross section presenting an outwardly opening groove 34 and an inwardly opening groove 35, each with flanges extending toward its mid portion. The outwardly opening groove 34 is uppermost of the tracks and receives the rollers 30 and 30' so as to slidably support the track for movement generally parallel to the inner surface 32 of each end wall. A spring 36 is attached to an eye 37 located at the inner end of the track, while this spring is attached to an eye 38 on the side wall 12 and tends to pull the track outwardly through the open side 27 of the casing.

The drawer designated generally 11 has opposite forward and rear walls 40 which are generally parallel to the forward and rear end walls 12. The bottom of the drawer 41 connects the forward and rear walls 40 of the drawer, while there is an inner side wall 42 extending between the forward and rear walls 40 and an outer side wall 43 which is of such shape and size that it forms a closure for the open side 27 of the casing. Suitable partitions 44, 45 and 46 may be located within the walls just described to divide up the carrying volume of the drawer.

The front and rear walls 40 of the drawer each have a wheel 47 mounted thereon at the same distance from the inner side wall 42 and at a distance nearer the inner side wall 42 than the outer side wall 43 to so weight the drawer that the outer side will tend to swing downwardly about the location of these wheels as a pivot. Each of these wheels 47 is mounted upon an axle 48 (see FIG. 2) fixed in its forward or rear wall 40 at this definite location, and in practice I have found that the distance of this axle 48 should be about two thirds of the distance from the outer side wall 43 to the inner side wall 42 or two thirds of the distance from the leading end of the drawer to the trailing end thereof as it is withdrawn. These two wheels 47, one on each wall 40 of the drawer, are received in the lower groove 35 of the track and will, when the drawer is in a horizontal position substantially in the plane of the rails, permit the drawer to be rolled along the tracks 33 into the case. The drawer must be swung up from the position shown in FIGURES 1 and 4 to substantially this horizontal position before it is slid into the case and before the rails are pushed into the case, and this is done by lifting the drawer by means of the handle 49 manually in order to do this. The fact that approximately one third of the drawer is mounted opposite the pivotal roller 47 from the lifting handle 49 assists in partially balancing the outer or forward part of the drawer in this swinging movement. As soon as the drawer is lifted to the horizontal position, it may be started into the case and the wheel 50 mounted at the upper end of the drawer may engage the undersurface 51 of the top 21 so as to roll therealong. As the drawer is moved into the case, inclined brackets 52 will engage the opposite end walls 40 of the drawer to center it in the case.

At the forward lower edge of the drawer, there will be sockets 54 extending outwardly from the ends 40 of the drawer and the edges of these sockets will be flared as at 55 so as to receive the ends 56 of the rail. After the drawer is lifted to horizontal position and rolled on the roller 47 along the tracks, the sockets will receive and engage the ends 56 of the tracks and then, as the drawer

is pushed in, the tracks will be moved inwardly along their rollers 30 and 30' until the drawer reaches its completely housed position at which point the front or outer side wall 43 of the drawer will provide a complete closure for the opening 27 of the casing.

Upon each of the ends 12 of the casing, a rod 60 is mounted by means of some bolts and spacers 61, and these rods 60 will project through openings 62 in the outer side wall 43 of the drawer. Each rod is provided with an opening therethrough which will receive a padlock 63 for locking the drawer against unauthorized withdrawal. When the drawer is completely housed as shown in FIGURE 3, the tension spring 36 will be under tension and in stretch condition as shown in FIGURE 3. Brackets 53 of L shape on the forward and rear walls of the drawer will pass beneath rods 60 and will prevent the drawer from being swung to a vertical position until the drawer is moved clear of the case.

It will be apparent that in order to withdraw the drawer from the casing that the padlocks will be removed, and then by engaging handle 49, the drawer may be pulled out of the casing and the tracks will also follow the drawer out of the casing by reason of the springs 36 contracting to pull the tracks along out of the casing as the drawer is drawn out of the casing. Should the operator tend to swing the drawer down, the roller 50 will engage the top 21 and it will permit movement without too great a drag therewith, while near the completion of withdrawal brackets 53 engaging rods 60 will serve the same purpose. When the tracks are pulled out to their full extent, the pin 37 which extends across the groove 33 in the track and also across the lower groove 35 in the track will engage the roller 30 and act as a stop to prevent further withdrawal of the track. After this occurs, the drawer will then move relative of the track until its roller 47 engages a bolt 65 which is positioned across the groove 35 of the track at which point the drawer will not be able to be moved further outwardly. This location, however, will be such that the trailing portion 66 of the drawer will swing clear of the casing so that it may be swung from a horizontal position through the intermediate position shown in FIGURE 4 to the vertical position shown in FIGURE 1. This arrangement permits the drawer to be moved out far enough to completely clear the vehicle upon which it is mounted so that the drawer may hang vertically as shown in FIGURE 1.

I claim:

1. A car top carrier comprising in combination:

(a) a casing having an open side and a pair of opposite

end walls with inner surfaces in generally vertical planes and a top wall,

(b) a track slidably mounted on each end wall for movement generally parallel with the inner surface thereof from within the casing through the open side thereof,

(c) a drawer of a size to be contained within said casing,

(d) sockets on said drawer to receive the ends of the track and support the drawer on the tracks and align the same therewith,

(e) means for pivotally and slidably mounting the drawer on said tracks for movement partially beyond the end of said tracks to disconnect the sockets therefrom and for pivoting when in such position from a position generally in line with the tracks to a position at right angles thereto,

(f) and a wheel at the upper inner end of the drawer to engage the top wall and roll therewith.

2. A car top carrier comprising in combination:

(a) a casing having an open side and a pair of opposite end walls with inner surfaces in generally vertical planes and a top wall,

(b) a track slidably mounted on each end wall for movement generally parallel with the inner surface thereof from within the casing through the open side thereof,

(c) a drawer of a size to be contained within said casing,

(d) sockets on said drawer to receive the ends of the track and support the drawer on the tracks and align the same therewith,

(e) means for pivotally and slidably mounting the drawer on said tracks for movement partially beyond the end of said tracks to disconnect the sockets therefrom and for pivoting when in such position from a position generally in line with the tracks to a position at right angles thereto.
